US0D1070846S

(12) **United States Design Patent** (10) **Patent No.:** **US D1,070,846 S**
(45) **Date of Patent:** **** Apr. 15, 2025**

(54) **PORTABLE COMPUTER**

(71) Applicant: **Lenovo (Beijing) Limited**, Beijing (CN)

CN 304974852 * 1/2019
CN 305216876 * 6/2019

(Continued)

(72) Inventor: **Libo He**, Beijing (CN)

(73) Assignee: **Lenovo (Beijing) Limited**, Beijing (CN)

(**) Term: **15 Years**

(21) Appl. No.: **35/518,899**

(22) Filed: **Sep. 28, 2023**

(80) **Hague Agreement Data**

Int. Filing Date: **Sep. 28, 2023**

Int. Reg. No.: **DM/232655**

Int. Reg. Date: **Sep. 28, 2023**

Int. Reg. Pub. Date: **Nov. 3, 2023**

(30) **Foreign Application Priority Data**

Mar. 29, 2023 (CN) 202330162031.7

(51) **LOC (15) Cl.** **14-02**

(52) **U.S. Cl.**

USPC **D14/315**

(57) **CLAIM**

The ornamental design for a portable computer as shown and described.

DESCRIPTION

1.1 is a front view of a portable computer showing the new design;

1.2 is a back view thereof;

1.3 is a left side view thereof;

1.4 is a right side view thereof;

1.5 is a top view thereof;

1.6 is a bottom view thereof;

1.7 is a top perspective view thereof;

1.8 is a right view of closed state thereof;

1.9 is a perspective view of closed state thereof; and

1.10 is a perspective view of state of use thereof.

The broken lines shown in the drawings illustrate portions of the portable computer that form no part of the claimed design.

1 Claim, 10 Drawing Sheets
